Primary Examiner — Catherine Tuttle(74) *Attorney, Agent, or Firm* — Andrus Intellectual Property Law, LLP**CLAIM**

The ornamental design for a bottle, as shown and described.

DESCRIPTION

FIG. 1 is a front isometric view of a bottle;

FIG. 2 is a back view thereof;

FIG. 3 is a front view thereof;

FIG. 4 is a left side view thereof;

FIG. 5 is a right side view thereof;

FIG. 6 is top view thereof; and,

FIG. 7 is a bottom view thereof.

The broken lines in FIGS. 1-6 are included for the purpose of illustrating associated pump closure elements that form no part of the claimed design.

1 Claim, 5 Drawing Sheets(56)
